United States Patent Office

Des. 212,079
Patented Aug. 27, 1968

212,079

BACKPLATE OR THE LIKE

Lionel C. Algoren, Evanston, Ill., assignor to National Lock Co., Rockford, Ill., a corporation of Delaware

Filed Dec. 14, 1967, Ser. No. 9,777

Term of patent 14 years

(Cl. D10—8)

FIG. 1

FIG. 2.

FIG. 3.

FIG. 4.

FIG. 2 is an edge elevational view thereof;

FIG. 3 is a rear elevational view thereof; and

FIG. 4 is a cross sectional view thereof taken on the line 4—4 of FIG. 1.

I claim:

The ornamental design for a backplate or the like, substantially as shown.
